(57) CLAIM

The ornamental design for a cup as shown and described.

DESCRIPTION

FIG. 1 is a front elevation view of a rotationally symmetric cup according to my new design;

FIG. 2 is a bottom plan view thereof; and,

FIG. 3 is a top plan view thereof.

The grayscale shading depicts a contrast which is part of the claimed design without claiming any particular color.

The portions of the cup shown in broken lines form no part of the claimed design.
